ARTICLE OF JEWELRY

Geiza B. K. Toth, Hopatcong, N. J., assignor to
 Cohn & Rosenberger, Inc., New York, N. Y., a
 corporation of New York

Application June 23, 1938, Serial No. 215,322

6 Claims. (Cl. 63—2)

My invention relates to a new and improved article of jewelry.

One of the objects of my invention is to provide a combination device which includes a frame, a plurality of clips, and a supplemental brooch.

Another object of the invention is to provide a device having parts which can be assembled or detached so that the device can be used for numerous ornamental purposes.

Another object is to provide a device of simple and durable construction, which can be manufactured readily and at low cost.

Other objects of my invention will be set forth in the following description and drawings which illustrate a preferred embodiment thereof, it being understood that the above statement of the objects of my invention is intended generally to explain the same without limiting it in any manner.

Fig. 1 is an inner plan view of the complete device.

Fig. 2 is a sectional view on the line 2—2 of Fig. 1.

Fig. 3 is a side elevation of Fig. 1, with the supplemental brooch removed, the pin of the frame being shown in the inoperative or vertical position.

Fig. 4 is a side elevation of the supplemental brooch which is an element of the complete assembled article which is shown in Fig. 1.

Fig. 5 is an outer plan view of the device illustrated in Fig. 1, the representation of part of the supplemental brooch being omitted.

Fig. 6 is a section similar to Fig. 2 with the supplemental brooch removed.

Fig. 7 is a sectional view on the line 7—7 of Fig. 2.

Fig. 8 is an inner plan view of the supplemental brooch which forms part of the complete device.

Fig. 9 is a plan view of the frame of the device.

The device comprises a frame 9 having a median lateral bar 9a, an inner closed semi-elliptical shaped bar 9b on the right and a similarly shaped bar 9c on the left. The inner bars 9b and 9c are connected to the frame 9 by means of intermediate integral webs 9k. The frame 9 is thus provided with median apertures 9d and 9e, and end apertures 9f and 9g. A pin 7 is pivotally connected to a lug 9h of the frame 9 and the usual catch 8 is provided for holding the pin 7 in the operative position which is shown in Fig. 1 and also in Fig. 9.

A pair of identical clips 1 and 2 can be connected to the frame 9 or be detached therefrom.

The ornamental bodies of clips 1 and 2 are respectively provided with locking bars 12 and 13 which are respectively connected to said clips 1 and 2, by means of hinges 10 and 11. These hinges 10 and 11 may be of the well known construction and they may include a suitable spring or springs (if desired) whereby each locking bar 12 and 13 will be held yieldingly in the operative position shown in Fig. 2, or in the inoperative position shown in Fig. 6. Hinges of this type are well known per se so that no specific description thereof is required.

The locking bars 12 and 13 can be respectively inserted through the apertures 9e and 9d and said bars can then be turned to the horizontal or locking position shown in Fig. 1. The locking bars 12 and 13 are of frame-like construction, and each of them is provided with five integral prongs, said prongs being designated by the respective reference numerals 12a and 13a.

As shown in Fig. 9, the webs 9k divide the space between the body of the frame 9 and the inner bars 9b and 9c into a series of spaced edge-openings. When the locking bar 12 is closed upon the frame, the two prongs 12a which are adjacent the base of the bar 12 enter the edge-openings which are directly adjacent the median lateral line of the frame and said prongs can closely abut or even contact with the adjacent webs 9k, which are directly adjacent median bar 9a. The next pair of prongs 12a enter the next pair of edge-openings of the frame 9. The top or outer prong 12a is located inwardly of the adjacent part of the inner bar 9b, adjacent the end-web 9k, and said outer prong may be close to or even abut inner bar 9b, and said prong enters a suitable recess which is provided in the body of the respective clip, as shown in Fig. 2. The base of the hinge then abuts the faces 98 of the inner bar 9b. This method of assembly holds the clip firmly in position, with little or no relative movement between the clip and the frame.

The supplemental brooch 5 is shaped to fill the spaces 4 of the open portions of the ornamental bodies of the clips, which bodies are the face members of the complete assembly shown in Fig. 1. The body of said supplemental brooch 5 also overlies the adjacent portions of the bars 12 and 13. The resilient metal pin 14 of the supplemental brooch 5 is pivotally connected thereto by means of a lug 5a and said pin 14 can be engaged by the usual catch 15, so as to hold the supplemental brooch firmly in position.

As shown in Fig. 2, the bodies of the clips 1 and 2 are provided with projections adjacent 55

the median lateral line of the frame 9, and these 5 projections fit in a recess of the body of the supplemental brooch 5, so that the brooch 5 is held against shifting relative to the clips 1 and 2 by means of said interfitting parts, in addition to the holding action of the resilient pin 14.

When said resilient pin 14 is secured to the catch 15, it may be slightly bent so that the 10 spring action of said pin 14 holds the supplemental brooch firmly in position.

10 The irregular edge of the body of the brooch 5 is indicated by the reference numeral 6. There 15 may be spaces between the body of the brooch 5 and the edges of the openings in the locking bars 12 and 13, when all the parts are assembled.

15 Therefore when all the parts are assembled as illustrated in Figs. 1, 2 and 5, the outer faces 20 of the body of the brooch 5 and of the clips 1 and 2, form a substantially continuous outer 25 surface. The outer faces of the bodies of the clips, and of the body of the brooch 5, may be decorated with suitable jewels or the like which are not shown in the drawings. The complete 30 assembly can be connected to a garment by means of the pin 7. The brooch 5 can be readily removed from the assembly so that it can be used separately, and the remaining assembled elements can also be used as a brooch. Likewise the 35 clips 1 and 2 can be separate from the frame 9 and the said clips can be connected to a garment by means of the prongs 12a and 13a.

30 The bodies of the clips are provided with openings or recesses and the prongs of the locking bars of said clips can enter said openings or recesses, when the clips are used separately.

35 A highly ornamental and useful article can thus be manufactured at low cost and used for numerous ornamental purposes.

40 While I have shown a preferred embodiment, it is clear that numerous changes and omissions can be made therefrom without departing from the spirit of the invention.

45 For example the members 9a and 9b and 9c can be omitted as it is sufficient if the prongs 12a and 13a abut or are located close to the inner edge of the body of the frame 9, when the parts are assembled. Likewise any suitable 50 means can be used for connecting the clips to the frame.

55 I claim:

1. An ornamental article comprising a main frame having means adapted to connect the same to a garment, a pair of clips each of which has a body and a locking bar turnably connected to said body at an edge of said body, said main frame and said clips having cooperating means adapted to hold said clips assembled with said main frame and with said edges of the bodies of said clips adjacent each other, the bodies of said clips having openings, a brooch having a body overlying the openings of the bodies of said clips, said brooch having holding means adapted to hold the same detachably assembled with said main frame and with said clips.

60 2. An ornamental article comprising a main frame, a pin pivotally connected to said main frame, a catch mounted on said main frame and adapted to hold the pin in locking position, said main frame having a body which is provided with a median lateral bar, said frame also having inner bars which are spaced from the body of said main frame, said inner bars having lateral extensions which are adjacent and which are spaced from said median lateral bar, so that

5 said main frame has adjacent openings located at each side of said median lateral bar and said frame also has additional openings which are spaced outwardly from said adjacent openings and said frame also has edge openings between the body of said frame and said inner bars, a pair of clips each of which has a body and a locking bar turnably connected to said body at an edge of said body, each said locking bar having its inner face provided with prongs, each said locking bar being shaped to be inserted through one of said adjacent openings, each said locking bar having some of its prongs located in said edge openings when it is in closed position and having one of its prongs substantially 10 abutting the inner edge of said inner bar when said locking bar is in closed position, the bodies of said clips and the locking bars thereof having openings which register with said additional 15 openings of the frame when the locking bars are 20 in closed position, a supplemental brooch having a body which overlies said median lateral bar and the adjacent portions of the bodies of the clips and which also overlies the openings in the bodies of said clips, the body of said supplemental brooch having a pin turnably connected 25 thereto and a catch to hold said pin, the pin of the supplemental brooch abutting the inner faces of said locking bars and holding the supplemental brooch in position when said pin engages its 30 catch.

3. An ornamental article comprising a main frame having means adapted to connect the same to a garment, a pair of clips each of which has a body and a locking bar turnably connected 35 to said body at an edge of said body, said main frame and said clips having cooperating means adapted to hold said clips assembled with said main frame and with said edges of the bodies of said clips adjacent each other, the bodies of said 40 clips having openings, a brooch having a body overlying the openings of the bodies of said clips, said brooch having holding means adapted to hold the same detachably assembled with said main frame and with said clips, the inner face of 45 the body of said brooch and the outer faces of the bodies of said clips being shaped to interfit.

4. An ornamental article comprising a main frame having means adapted to connect the same to a garment, a pair of clips each of which has a body and a locking bar turnably connected to said body at an edge of said body, said main frame and said clips having cooperating means adapted to hold said clips assembled with said main frame and with said edges of the bodies of said clips adjacent each other, the bodies of said 55 clips having openings, a brooch having a body overlying the openings of the bodies of said clips, said brooch having holding means adapted to hold the same detachably assembled with said main frame and with said clips, portions of the inner edges of the bodies of said clips and of the outer edge of the body of the brooch being shaped 60 to interfit substantially.

5. An ornamental article comprising a main 65 frame having means adapted to connect the same to a garment, a pair of clips each of which has a body and a locking bar turnably connected to said body at an edge of said body, said main frame and said clips having cooperating means 70 adapted to hold said clips assembled with said main frame and with said edges of the bodies of said clips adjacent each other, the bodies of said clips having openings, a brooch having a body overlying the openings of the bodies of said clips, 75

- 5 said brooch having holding means adapted to hold the same detachably assembled with said main frame and with said clips, the inner face of the body of the brooch having a lateral recess at the median portion thereof, the outer faces of the bodies of the clips having projections at said edges of said bodies, said projections fitting substantially in said recess.
6. An ornamental article comprising a main frame having means adapted to connect the same to a garment, a pair of clips each of which has a body and a locking bar turnably connected to said body at an edge of said body, said main frame and said clips having cooperating means adapted to hold said clips assembled with said main frame and with said edges of the bodies of

5 said clips adjacent each other, the bodies of said clips having openings, a brooch having a body overlying the openings of the bodies of said clips, said brooch having holding means adapted to hold the same detachably assembled with said main frame and with said clips, the body of said brooch having a catch at the inner face thereof, said holding means consisting of the pin which is pivotally connected to the body of the brooch and which is adapted to be engaged by said catch, said pin being shaped to be moved rearwardly of the frame by inserting the pin through a pair of aligned openings of the frame and of a body of a clip.

GEIZA B. K. TOTH. 15
